CLAIM

I claim the ornamental design for a portfolio, as shown and described.

DESCRIPTION

FIG. 1 is a perspective view of a portfolio showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right-hand side elevational view thereof; and,

FIG. 7 is a left-hand side elevational view thereof.

The evenly spaced dashed lines shown in FIGS. 1, 2, 3, and 7 represent stitching and are part of the claimed design.
